UNITED STATES PATENT OFFICE.

WORTHY C. BUCKNAM, OF JERSEY CITY, NEW JERSEY, ASSIGNOR TO DAVIS-BOURNONVILLE COMPANY, OF NEW YORK, N. Y., A CORPORATION OF NEW YORK.

BLOWPIPE APPARATUS.

1,078,412.

Specification of Letters Patent. Patented Nov. 11, 1913.

Application filed January 28, 1913. Serial No. 743,768.

To all whom it may concern:

Be it known that I, WORTHY C. BUCKNAM, a citizen of the United States, and a resident of Marion, Jersey City, in the county of Hudson and State of New Jersey, have invented certain new and useful Improvements in Blowpipe Apparatus, of which the following is a specification.

This invention relates more especially to 10 torch or blow-pipe apparatus of the character used for metal cutting. As is well known in the art, an apparatus of this character directs jets of two kinds against the work, and when relative movement is produced between the work and the jets in the desired direction the metal is severed along such line. The jets comprise one or more comparatively small and intensely hot heating flames, composed of a mixture of 20 oxygen with acetylene, hydrogen or other suitable combustible gas, which locally heat the metal to a high temperature, and a jet of pure oxygen which strikes the heated region and instantly oxidizes it.

The object of this invention is to provide 25 an apparatus of this character in which the jet-delivering means is mechanically supported and guided in such manner as to make it possible to cut slots or non-circular openings expeditiously and accurately.

More especially the object is to provide 30 a simple and compact device which may be attached to a rail or other bar for cutting slots or non-circular openings therein.

While the apparatus is particularly designed 35 for cutting slots or openings, the principles of construction may be utilized for producing various irregular, curved or circuitous cuts.

An embodiment of the invention will now 40 be briefly described, after which the features of novelty will be more particularly pointed out in the claims. The said embodiment is illustrated in the accompanying drawings, wherein:

Figure 1 is a front elevation of the device applied to the end of a rail, the cover plate and cam carried thereby and the torch being removed; Fig. 2 is a plan view, with 50 the cover plate in place; Fig. 3 is a vertical transverse section on the line 3—3 of

Fig. 1; Fig. 4 is a semi-diagrammatic view illustrating the operation; Fig. 5 is a section on the line 5—5 of Fig. 1, showing the torch; and Fig. 6 is a detail cross-sectional view through the torch holder.

The apparatus as constructed for rail-slitting has a clamp formed to straddle or embrace the rail and grip opposite sides of the web, the same comprising a bifurcated or bowed body 10, carrying on one member a shoe 11 and on the other member a lever-clamping device 12. The shoe is a centralizing member formed to fit between and against the ball and flange of the rail, so as to locate the center of the device opposite the middle of the height of the web; and it is removable and replaceable, so that appropriate shoes may be used for different sizes of rail. To this end it is mounted against a face 13 on the inner or rail side of its limb of the body of the clamp and is provided with a slot receiving a rib 14, one or more screws 15 serving to hold the shoe thereon.

To the outer side of this limb of the clamp is rigidly secured an offset 16 on a ring or frame 17, which is thus supported vertically opposite the side of the rail. The inner edge 18 of this frame ring constitutes a bearing of large diameter on which a rotary wheel or disk 19 is rim-journalized, that is to say, the wheel 19 is rotatably mounted at its outer part on the open support 17.

The member 19, which constitutes a driver or carrier for moving the torch 20 about the axis of the wheel, is preferably built up of a ring 21 engaging the bearing 18, a second ring 22 co-operating with the first to receive the edge 18 between them, thus holding the wheel against displacement, and a disk 23 which has a circular shoulder 24 that fits into both rings and centers them with reference to each other. The three parts are suitably connected by screws or the like. The ring 22 is provided at its periphery with gear teeth 25, so that the whole rotary member may be regarded as a gear rim-journalized on the supporting frame 17. The gear teeth 25 are meshed by a worm 26 on a shaft 27 journalized in bearings 28 on the support and driven

through miter gears 29 by a wheel crank handle 30, the shaft of which is journaled in the support at 31. This gearing enables the rotary member to be driven by hand at uniform speed, and the latter in turn moves the torch at approximately uniform speed, with such variation as is produced by the cam 32, which variation is not, however, sufficient to impair the nature of the cut.

The cam 32 extends around the axis of the rotary member 19, and is of such formation as to guide the torch so that its jets travel along the appropriate path for cutting the desired form of slot or other opening. Obviously the shape of the cam will be varied according to the nature of the cut desired. This cam is stationary and is preferably secured to the inner side of a cover plate or ring 33, which is suitably secured to an outward-projecting rim 34 on the supporting ring 17, the parts 17 and 33 thus forming an annular casing. The torch or blow-pipe is mounted on a part 35 which is movably connected to the driver 19 so as to be capable of moving toward and from the axis thereof as the driver rotates. It is preferably in the form of a slide having its end portions mounted to reciprocate in guides 36 on the ring 23. The torch passes through the middle of this part and through an enlarged opening 37 in disk 23, which is sufficiently large to afford the requisite scope of lateral movement for the torch. The part 35, carrying the torch, is guided by engagement with the cam 32, and to this end it is provided near one end with a roller 38 which travels on the cam. The latter, it will be seen, is in the nature of a track extending around the axis of the rotary carrier or driver so as to guide the torch carrier, so that the torch travels in the proper path. For convenience the cam is formed of two cam rings and the roller 38 travels in the slot between them. The torch is located on the part at a point nearer the axis of rotation than the contact portion 38, so that the path which is described by the torch under the guidance of the cam is different both from the outline of the cam and from the circular movement of the driver. Thus, the cam illustrated is of the appropriate formation for producing the shape of slot indicated at 39 in Fig. 4. In order to adjust the torch exactly to the desired path it is mounted in a holder 40, which is adjustable on the part 35 toward and from the axis of rotation by means of a screw 41. The cam pieces 32 are removable and replaceable by detaching the cover plate 33 and substituting another carrying a different cam, so that by varying the shape of the cam the jets of the torch can be caused to travel along a different path.

The length of the slot cut in the end of the web of the rail is determined by a gage 42, 65 in the nature of a rod fixed to the clamp body

10 and extending lengthwise of the rail to the end thereof, being provided with a laterally-projecting head 43 which contacts with the end of the rail when the clamp has been positioned far enough from the rail end. 70

The holder 40 is a tubular socket provided with a centralizing clamp which avoids laterally displacing the torch in the act of tightening the holding means. The clamping means is shown as comprising a bushing 75 43 having a plurality of equally-spaced slots 44 cut inward from each end, the members of the two sets of slots alternating with each other so as not to weaken the metal unduly, and being preferably extended past 80 each other at their inner ends. The ends of the bushing are beveled and engage beveled surfaces 45, 45^a, formed on one end of the body of the holder 40 and on a screw cap or ring 46, respectively. The latter when 85 screwed onto the body of the holder by virtue of the beveled surfaces squeezes both the front and back portions of the bushing against the cylindrical body of the torch 20. When the cap is unscrewed the resilience of 90 the metal of the bushing causes it to open slightly, releasing the grip on the torch.

The gas cutting means may be of any suitable or usual construction, and consists essentially of a device or assemblage for delivering heating and oxygen jets against the work so as to rapidly oxidize or cut the metal in the well known manner. The heating and cutting jet orifices are indicated at 47, 48, respectively, and the conduits for 100 leading gas to supply these jets pass through the part 35 and carrier 19, and inside of the bearing 18 and the cam track 32, the openings inclosed by the bearing and cam track permitting unobstructed movement of the 105 torch and its connections both around the axis of the rotary member 19 and toward and from the same. The gas cutting means is shown as a usual form of torch provided with a cylindrical body held in the holder 110 40 and inclosing the pipes 49, 50, 51, which lead oxygen for the cutting jet, oxygen for the heating jet, and acetylene for the heating jet, respectively. The torch embodies usual provisions, not shown, for causing the oxygen and acetylene from pipes 50 and 51 to mix before passing out of the heating jet orifice 47. At the rear the torch has connections 52, 53, 54, for attachment to flexible pipes leading from suitable sources of supply. Any other suitable form of torch may be used. While the heating and cutting jets are shown delivered from a single nozzle, distinct nozzles might be employed.

The torch may be moved forward or backward in its holder to position its jet orifices at the proper distance from the rail web; furthermore, the torch is removable and replaceable as a whole.

In operation, the device is first clamped

to the rail, near the end thereof, and the rotary member is turned until the tip of the torch is at or beyond the end of the web. The rotary member is then rotated at even speed so that the torch guided by the cam causes its jets to travel straight inward from the end of the web, then turn and move straight outward again. The path along which the jets operate can be varied by varying the cam; and in general the construction of the apparatus can be varied considerably to adapt it for different kinds of work, where it is desired to cut along irregular or variously curved lines or lines partly curved and partly straight. A similar or modified apparatus could be used with an autogenous welding torch where it was desired to weld along a line neither straight nor circular.

In Fig. 4, which illustrates the rail-slitting device and its operation in a semi-diagrammatic manner, the cam surfaces are shown at 32 and the roller at 38. The part 35 is indicated diagrammatically, and the torch carried by it is indicated by the circle 20, the positions of the heating and cutting jets being shown at 47, 48, respectively. The outline of the slot cut by the oxygen jet with the assistance of the heating jet or jets is shown at 39. The axis about which the driver 19 rotates is indicated at α . It will be understood that the part 35 turns with the wheel 19 and is constrained by the cam 32 to slide in and out on the wheel always in radial directions. The result is that the jets, or rather the cutting jet travels along the path represented by the outline of the slot.

What I claim as new is:

1. The combination of a movable part having jet-delivering means, a guide adapted to confine said jet-delivering means to a circuitous non-circular path, and a driver mounted to rotate in fixed relation to a fixed axis for propelling said member along said guide.

2. Means for cutting non-circular openings in metal, comprising a suitable stationary support, a rotary member journaled thereon, a track or cam determining the outline of the opening, and gas-cutting means moved around by said rotary member under the guidance of the cam.

3. The combination of a rotary member mounted to rotate in fixed relation to a fixed axis, a stationary cam, and a torch support connected movably to said member and guided by said cam.

4. An apparatus of the character described, comprising a suitable stationary support, a guide, a member journaled on the support to rotate relatively to said guide, a part mounted on said rotary member and having a contact portion to travel along said guide so as to be moved thereby relatively to

said rotary member as the latter turns, and jet-delivering means on said part.

5. The combination of a rotary driver, a cam, a part connected movably to said driver and having a contact portion to travel on said cam, and jet-delivering means on said part and spaced from the contact portion thereof, whereby the jet-delivering means is caused to travel in a predetermined path differing both from the outline of the cam and from the circular movement of the driver.

6. An apparatus of the character described, comprising a suitable support, a cam, a member journaled on the support, means for rotating said member relatively to the cam, a part mounted movably on said member and having a contact portion to travel on said cam, and jet-delivering means on said part at a point nearer the axis of rotation of the rotary member than said contact portion.

7. An apparatus for slotting or cutting out non-circular openings in metal, comprising a rotary journaled member, a stationary guide extending around the axis of rotation thereof, and a part movable on said member and traveling on said guide, so as to be moved by the latter relatively to said rotary member, and having heating and oxygen jets.

8. An apparatus of the character described, comprising a suitable support, a member mounted to rotate on a suitable bearing on said support, and a cam track disposed in a plane transverse to the axis of rotation of said member, in combination with a mechanical drive geared to said rotary member for turning the same in a substantially uniform manner, a part propelled by said rotary member and guided relatively thereto by means of a portion traveling on said cam track, and jet-delivering means carried by said part and directed in general parallelism to said axis.

9. The combination of a carrier mounted to rotate in fixed relation to a fixed axis, a torch movable thereon, and means for predeterminedly and automatically varying the distance between the torch and the axis about which the carrier rotates during the rotation thereof so as to cause the torch to move in a predetermined path.

10. The combination of means for delivering heating and oxygen jets, a member journaled to rotate in fixed relation to a fixed axis and adapted to move said means about said axis, and guide means for causing said jet-delivering means to move relatively to said member and to said axis in accordance with a predetermined line of cut while said part rotates.

11. In an apparatus of the character described, a member mounted to rotate in fixed relation to a fixed axis, a part slidably

guided thereon, jet-delivering means carried by said part, and a guide engaged by said part.

12. An apparatus of the character described comprising a support, a carrier rim-journalized thereon, a torch on the carrier movable nearer to or farther from the axis thereof, and a stationary guide for confining said torch to a predetermined non-circular path.

13. An apparatus of the character described comprising a support having a bearing, a rotary member journalized therein, a torch movable laterally on said member within said bearing toward and from the axis of rotation, and a stationary guide controlling such movement of the torch.

14. An apparatus of the character described, comprising a support, a circular carrier journalized thereon, a slide movable in and out on said carrier, a cam controlling the movement of said slide on the carrier, and a torch mounted on said slide.

15. An apparatus of the character described, comprising a support having a bearing, a wheel rotatably supported at its outer part by said bearing, a cam track disposed about the axis of said wheel, a part in contact with said cam track and movable toward and from the center of said wheel, and jet-delivering means with suitable supply conduits carried by said part and passing freely through said wheel and within said bearing and cam track.

16. An apparatus of the character described, comprising a support having an opening, a carrier wheel rim-journalized thereon and being open in its interior and provided with transverse guiding means, a torch slide engaging said guide means, and a cam track on the support engaged by a roller on the slide.

17. An apparatus of the character described, comprising a supporting frame, a gear wheel rim-journalized thereon, driving means engaging with said gear wheel, a cam track disposed about the axis of said gear wheel, and a torch movable toward and from the center of said gear wheel and having a contact member traveling on said cam track.

18. An apparatus of the character described, comprising a supporting frame, a circular member rotatable thereon, a cam track housed in the frame, and a jet-carrying part movably connected with the circular member and having a contact portion traveling on said cam.

19. An apparatus of the character described, comprising a supporting frame having a cover plate, a track cam mounted on the inside of the cover plate, a wheel rotatable in said frame, and a torch movable toward and from the center of said wheel under the influence of said cam.

20. In apparatus of the character described, the combination of a rotary member, a track, and a torch-bearing part movably connected to the rotary member and moved thereby around the track, said part comprising a portion to travel on the track and a portion adjustable relatively thereto and carrying the torch.

21. A slot or hole cutting machine, comprising a rotary member, a track, a part 75 movable on the rotary member and movable thereby around the track which causes said part to move in and out on the rotary member, and a torch holder adjustable on said part.

22. A device for slotting the ends of rails and the like, comprising a support having rail clamping means, a member mounted to rotate on said support opposite the side of the rail, a cam or track on the support determining the outline of the slot, gas-cutting means moved around by the rotary member and guided by the track, and a gage on the support positioned to contact with the rail and determine the depth of the slot.

23. Cutting apparatus comprising gas-cutting means, a member rotatable in fixed relation to a fixed axis for moving said means about its axis, and a removable and replaceable means for guiding said gas-cutting means so as to move relatively to said member and its axis while being driven thereby.

24. Means for cutting slots or other non-circular openings of various kinds, comprising a suitable support, a member mounted to rotate thereon in fixed relation to a fixed axis, a removable and replaceable cam track on the support, the plane of said cam track being transverse to said axis, and jet-delivering means propelled by said rotary member and guided by said cam track so as to have predetermined movement relative to said member, said jet-delivering means being directed transversely to the plane of the cam track.

25. A rail-slitting device comprising a support adapted to be applied to a rail or the like, a rotary member mounted on a suitable bearing on said support to rotate about a horizontal axis transverse to the rail, 115 means for driving said rotary member, a cam mounted on the support, and jet-delivering means mounted so as to be propelled laterally by said rotary member and having a traveler engaging said cam so as to be 120 guided thereby relatively to said member.

26. A rail-slitting device comprising a support adapted to be applied to a rail or the like, a rotary member mounted on a suitable bearing on said support to rotate about a horizontal axis transverse to the rail, means for driving said rotary member, a cam mounted on the support, and a slide

engaging said rotary member and having contact with said cam and carrying a torch holder, whereby a torch may be propelled laterally so as to cut a predetermined slot 5 or opening.

27. The combination of a support, a rotary carrier rim-journalized thereon, a blowpipe passing through and movable across said carrier, and means for moving said

torch relatively to the carrier as the latter 10 rotates.

In witness whereof I have signed my name in the presence of two subscribing witnesses.

WORTHY C. BUCKNAM.
